REEL FOR LINE CASTING

David F. Marriott, Pacific Palisades, and Le Roy T. Carter, Torrance, Calif., assignors to Brandex, Inc., Torrance, Calif., a corporation of California

Filed Oct. 24, 1960, Ser. No. 62,600

Term of patent 3½ years

(Cl. D31—4)

FIGURE 1 is a side elevational view of a reel device for line casting embodying our new design, the opposite side, not shown, being substantially the same;

FIGURE 2 is a front elevational view thereof;

FIGURE 3 is a cross-sectional view thereof; and

FIGURE 4 is a cross-sectional view thereof taken on the line 4—4 of FIGURE 2.

We claim:

The ornamental design for a reel for line casting, substantially as shown.
